UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR CONNECTING GUN-CARRIAGES TO LIMBERS OR FORE-CARRIAGES.

1,310,145.

Specification of Letters Patent.

Patented July 15, 1919.

Application filed August 21, 1918. Serial No. 250,861.

To all whom it may concern:

Be it known that I, EUGÈNE SCHNEIDER, a citizen of the French Republic and a resident of 42 Rue d'Anjou, Paris, France, have 5 invented a new and useful Improvement in Apparatus for Connecting Gun-Carriages to Limbers or Fore-Carriages, which invention is fully set forth in the following specification.

- 10 This invention relates to apparatus for connecting trails to gun limbers or fore-carriages, and it has for its object to provide an improved apparatus for assuring the elasticity of the support and of the 15 coupling between gun carriage trails or false trails and gun limbers or fore-carriages generally, of the kind disclosed in my earlier application Serial No. 217,185, filed Feb. 14, 1918.
- 20 The present improved apparatus is characterized by the feature that the yoke eye, which engages the pivot pin of the fore-carriage, rests in its turn upon an elastic support located between it and the fore- 25 carriage.

The invention is capable of receiving a variety of mechanical expressions, two of which are shown on the accompanying drawings, but it is to be expressly understood 30 that the drawings are for purpose of illustration only and are not to be construed as a definition of the limits of the invention, reference being had to the claims for that purpose.

35 In the drawings:

Figure 1 is a vertical longitudinal section of an apparatus, of the type disclosed in my aforesaid earlier application, for the support and connection of a gun carriage trail, 40 illustrating one embodiment of the improved supplementary elastic support of the present invention;

Fig. 2 is a side elevation illustrating the supporting and connecting apparatus applied to a false trail and showing another form of supplementary elastic support;

Fig. 3 is a vertical cross section on a larger scale on the line III—III of Fig. 2.

Referring first to the embodiment illustrated in Fig. 1, the gun carriage trail D carries an elastic stud E located on the trail and adapted to bear upon a fixed circular track C located on the rigid fore-carriage whereof A is the axle. The yoke apparatus 55 consists of an eye H on the trail adapted to

engage the pivot pin I, and, as in my earlier application, is movable along the axis of said trail in a button-hole-shaped slot d. Elastic supports or connections are provided between the movable eye H and two fixed 60 points D¹, D² of the trail by the use of springs K as shown.

According to the present invention, a supplementary elastic support is provided for the movable eye H. For this purpose a ring 65 L is guided on the pivot pin I by means of a tenon M engaging in a longitudinal groove i in the said pivot pin. A coiled spring N bears at its upper end on a collar or flange on the ring L, and is held at its lower end 70 in a dish-shaped socket O suitably attached to the fore-carriage.

In the form illustrated in Figs. 2 and 3, the supplementary support for the yoke eye H comprises a cross member L¹ engaging 75 the pivot pin I by means of an eye formed in its central portion. Rods P are attached to the ends of the said cross member and are guided at their lower ends in sockets Q projecting from the fore-carriage. N¹ are 80 Belleville washers arranged around the rods P, said washers being shown contained in housings provided by said sockets Q and caps S on the cross member L adapted to telescope within said sockets. 85

While the embodiments illustrated on the drawings have been described with considerable particularity, it is to be understood that the invention is not to be restricted thereto as the same is capable of receiving 90 a variety of mechanical expressions. Reference is to be had to the appended claims for a definition of the limits of the invention.

What is claimed is:—

1. In an apparatus for connecting a trail to a limber or fore-carriage, the combination with the trail, the fore-carriage, the pivot pin on the fore-carriage and the yoke-eye of the trail, of an elastic supporting device 100 between said yoke-eye and the fore-carriage comprising a member on said pivot pin with which said yoke-eye is adapted to engage, and a spring between said member and the fore-carriage. 105

2. In an apparatus for connecting a trail to a limber or fore-carriage, the combination with the trail, the fore-carriage, the pivot pin on the fore-carriage and the yoke-eye of the trail, of an elastic supporting device 110 be-

tween said yoke-eye and the fore-carriage comprising a ring engaging the pivot pin and with which said yoke-eye is adapted to engage, and a spring between said ring and 5 a socket member on the fore-carriage.

3. In an apparatus for connecting a trail to a limber or fore-carriage, the combination with the trail, the fore-carriage, the pivot pin on the fore-carriage and the yoke-eye of 10 the trail, of an elastic supporting device between said yoke-eye and the fore-carriage comprising a transverse member on said pivot pin with which said yoke-eye is adapted to engage, and a plurality of springs be- 15 tween said member and the fore-carriage.

4. In an apparatus for connecting a trail to a limber or fore-carriage, the combination with the trail, the fore-carriage, the pivot pin on the fore-carriage and the yoke-eye 20 of the trail, of an elastic supporting device between said yoke-eye and the fore-carriage comprising a transverse member engaging the pivot pin and with which said yoke-eye is adapted to engage, a spring-retaining 25 member on the fore-carriage, and one or more springs between said transverse member and said spring-retaining member.

5. In an apparatus for connecting a trail to a limber or fore-carriage, the combination 30 with the trail, the fore-carriage, the pivot pin on the fore-carriage, the yoke-eye of the trail, and an elastic stud through which the trail bears on the fore-carriage, of an elastic supporting device between said yoke-eye and 35 the fore-carriage.

6. In an apparatus for connecting a trail to a limber or fore-carriage, the combination with the trail, the fore-carriage, the pivot pin on the fore-carriage, the yoke-eye of the 40 trail, and an elastic connection between said yoke-eye and the trail, of an elastic supporting device between said yoke-eye and the fore-carriage.

7. In an apparatus for connecting a trail to a limber or fore-carriage, the combination 45 with the trail, the fore-carriage, the pivot pin on the fore-carriage, the yoke-eye of the

trail, an elastic stud through which the trail bears on the fore-carriage, and an elastic connection between said yoke-eye and the 50 trail, of an elastic supporting device between said yoke-eye and the fore-carriage.

8. In an apparatus for connecting a trail to a limber or fore-carriage, the combination with the trail, the fore-carriage, the pivot pin on the fore-carriage and the yoke-eye of the trail, of an elastic supporting device between said yoke-eye and the fore-carriage comprising a transverse member engaging the pivot pin and with which said yoke-eye 60 is adapted to engage, a member on the fore-carriage, one or more pins carried by one of said members and slidably in the other of said members, and one or more springs between said members. 65

9. In an apparatus for connecting a trail to a limber or fore-carriage, the combination with the trail, the fore-carriage, the pivot pin on the fore-carriage and the yoke-eye of the trail, of an elastic supporting device between said yoke-eye and the fore-carriage comprising a transverse member engaging the pivot pin and with which said yoke-eye 70 is adapted to engage, a member on the fore-carriage, one or more springs between said members, and telescopic elements housing 75 said springs.

10. In an apparatus for connecting a trail to a limber or fore-carriage, the combination with the trail, the fore-carriage, the pivot pin on the fore-carriage and the yoke-eye of the trail, of an elastic supporting device between said yoke-eye and the fore-carriage comprising a member on said pivot-pin and maintained against rotation with respect 85 thereto, and one or more springs between said member and the fore-carriage.

In testimony whereof I have signed this specification,

EUGÈNE SCHNEIDER.
